ATTORNEY

WITNESS:

UNITED STATES PATENT OFFICE.

WALTER B. PHILLIPS, OF CLINTON, ILLINOIS.

FENCING MACHINE.

Application filed May 26, 1922. Serial No. 563,973.

To all whom it may concern:

Be it known that I, WALTER B. PHILLIPS, a citizen of the United States, residing at Clinton, in the county of De Witt and State 5 of Illinois, have invented new and useful Improvements in Fencing Machines, of which the following is a specification.

This invention relates to a combined post hole digger and wire winding device, the 10 general object of the invention being to provide means for actuating the device by power, preferably from a tractor to which the device is adapted to be connected so that it will be supported from the tractor.

Another object of the invention is to provide means for leveling the parts if the tractor is resting on unlevel ground and to provide means for placing the digger shaft perpendicular when the supporting frame for 20 the same is not level.

A further object of the invention is to provide means for driving the digger shaft at slow speed when the auger is moving downwardly and at faster speed when raising the 25 auger to empty the same.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a side view showing the device attached to a tractor.

Figure 2 is a top plan view of the same.

Figure 3 is a section on line 3-3 of Figure 1.

Figure 4 is a horizontal section on line 4-4 of Figure 3.

Figure 5 is a fragmentary sectional detail view;

Figure 6 is a perspective of one of the elements employed in the invention;

Figure 7 is a rear end elevation showing a 50 wire reel mounted upon the driven shaft, and

Figure 8 is a perspective of parts of the invention.

In these views, 1 indicates a frame which 55 is provided with the aligned shafts 2 and 3,

which act as pivots for pivoting the frame on the bars 4. These bars may be secured to a tractor, as shown in Figure 1 or to a portable gas engine or the like. The frame is adapted to be tilted on its pivots by the 60 lever 5 engaging the segment 6 on one of the bars 4. The shaft 2 has a belt pulley 7 thereon so it may be driven from the engine of the tractor or the other engine. This shaft is also provided with a friction wheel 65 8 which is slidably mounted on the shaft but is held against rotary movement thereon. A shaft 9 is journaled in the frame and a sleeve 10 is keyed to this shaft so it can slide thereon but cannot rotate thereon. A friction wheel is secured to each end of the sleeve, as shown at 11 and 12, these wheels being adapted to engage with the wheel 8 so that when one wheel is engaging said wheel 8 the sleeve and shaft 9 will be rotated in one direction and when the other wheel is engaging wheel 8 the sleeve and shaft will be rotated in an opposite direction. A lever 13 is provided for shifting the 70 wheel 8 on its shaft and a lever 14 for moving the sleeve 10 to a neutral position or to a position where either one or the other of the wheels 11 and 12 will be engaged by the wheel 8. Thus the shaft 9 can be driven in either direction or be permitted to remain 75 stationary by shifting the lever 14 and the shaft can be driven at different speeds by means of the lever 13 moving the wheel 8 so that it will engage the wheel 11 or the wheel 12 at different points on its diameter. 80

A circular plate 20 is secured to the outer end of the frame and the shaft 9 passes through said plate. Arc-shaped slots 21 are formed in this plate and teeth 22 are formed on a part of the circumference of the plate. A second circular plate 23 is adjustably secured to the first plate by means of the bolts 24 engaging the slots 21, the plate being adjusted by means of a lever 25 which is secured to the plate 23 and has 100 its pawl 26 engaging the teeth 22 in the first plate. A supporting block 27 is secured to the plate 23, said block having spaced perforated lugs 28, in one of which is rotatably mounted a gear 29 and in the other a screw 105 threaded bushing 30, said bushing being held against rotation by a bolt 31. A gear 32 is secured to the end of the shaft 9 and meshes with the gear 29. A screw-shaft 33 passes through the gear 29 and the bushing 110

30, the gear 29 being keyed to the shaft so that the shaft must turn with the gear but can have sliding movement therethrough. The bushing 30 being stationary will act as 5 a nut and cause the shaft to move longitudinally as it is being rotated by the gear 29. The shaft 33 is connected with the stem of the auger 34 by the universal joint 35 and the parts of this joint are detachably connected together so that the auger can be 10 removed from the screw-shaft.

From the above it will be seen that the movement of shaft 9 will be communicated to the screw-shaft so that the same will be 15 rotated and moved longitudinally to feed the auger to its work and at the same time rotate it. The auger will be fed downwardly slowly but will be moved upwardly rapidly and the auger can be emptied by turning 20 its stem on the joint 35. The speed at which the auger is actuated is controlled by the lever 13. By tilting the frame upon its pivots the parts can be leveled where the ground is not level and by means of the 25 lever 25 and its associated parts the screw-shaft can be placed perpendicular where the frame is not in a horizontal position.

By removing the auger from the screw-shaft and turning the plate 23 to place said 30 screw-shaft horizontally, a wire reel 36 may be placed on the screw shaft and secured thereon by a nut 37. Thus the device can be used for winding wire. In this case the bolt 31 would be loosened so that the bushing 30 can rotate and the bushing may be 35 connected with the screw-shaft by a bolt 38. Thus the bushing will rotate with the

shaft and will not cause it to move longitudinally.

I may also provide a forked bar 39 for 40 making the device useful in pulling up posts. This bar is fastened to a part of the tractor or to another support by a bolt which passes through the slot 40 in the bar. A bushing 41 is rotatably mounted in the bar and 45 this bushing is adapted to receive the screw-shaft 33, a part of the joint 35 engaging the bottom of the bushing. Thus when the screw-shaft moves upwardly it will carry the bar 39 with it and thus pull up the post 50 which is fastened by a chain 42 with the forked end of the bar.

It is thought from the foregoing description that the advantages and novel features of my invention will be readily apparent. 55

I desire it to be understood that I may make changes in the construction and in the combination and arrangement of the several parts, provided that such changes fall 60 within the scope of the appended claim. 65

What I claim is:—

In a mechanism of the character described, a frame, a disk arranged at one end thereof and fixed to the frame, rack teeth on the disk, a rotatable disk arranged 65 in opposed relation to the first disk, a lever carried thereby and provided with latch elements engageable in the rack teeth whereby to hold the rotatable disk in an adjusted position about its axis, bearings carried by 70 the rotatable disk and a rotatable shaft journaled in the bearings.

WALTER B. PHILLIPS.
